BUNDLING-MACHINE.

1,057,488.

Specification of Letters Patent. Patented Apr. 1, 1913.

Application filed September 15, 1910. Serial No. 583,169.

To all whom it may concern:

Be it known that we, ROBERT C. LOWRY and LOUIS F. WINTER, citizens of the United States, residing at New York city, New York, have invented certain new and useful Improvements in Bundling-Machines; and we do hereby declare the following to be a full, clear, and exact description of the invention, such as will enable others skilled in the art to which it appertains to make and use the same.

The invention relates to machines for binding or tying with wire articles such as shipping boxes, whereby the unauthorized and undetected opening of such boxes during shipment is prevented, or for binding or tying with wire bundles of laths, box-shocks, loose stock in the form of strips or blanks, and the like, and more particularly to improvements in machines of the type shown and described in United States Letters Patent to Lowry and Reynolds, #799,174 of Sept. 12th 1905, in which there is a bundling table suitably supported on legs, with a vertically reciprocating head-plate carrying presser arms adapted to clamp the bundle on the table within a loop of binding wire, and a twister adapted to twist together the ends of the loop to complete the tie. In such a machine it is of particular importance that the binding loop of wire should be placed around the bundle at right angles to the longitudinal axis thereof, since if the loop of binding wire is askew when it is first placed on the bundle, it will subsequently work loose. It is further important to provide for drawing the binding loop more tightly about the bundle than would be possible by hand alone.

The improved machine therefore provides means to insure that the binding loop shall lie at right angles to the bundle, and mechanism through which a strong leverage may be applied to tighten the wire.

The invention further provides improved construction of support for the reel which holds the coil of binding wire, whereby the over-running and tangling of the wire is prevented.

In order that the invention may be readily understood and carried into practice, reference is hereby made to the accompanying sheets of illustrative drawings, wherein—

Figure 1 shows the complete machine in 55 side elevation; Fig. 2 is an end elevation, looking at the bundling end of the machine; Fig. 3 is a sectional elevation on the line 3—3 of Fig. 1, looking in the direction of the arrows; Fig. 4 is a plan looking down 60 on the top of the machine; Fig. 5 is a sectional plan on the line 5—5 of Fig. 3 illustrating the construction of the mechanism for elevating and lowering the bundle clamp; Fig. 6 is a section on the line 6—6 65 of Fig. 4 illustrating the mechanism through which the leverage is applied to tighten the binding loop; Fig. 7 is a sectional plan on line 7—7 of Fig. 8, of the mechanism for winding up the loose wire on the wire reel as the loop is tightened; Fig. 8 is a sectional elevation of the wire reel and the winding-up mechanism; Figs. 9 and 10 are fragmentary elevations showing different positions of the elevating and lowering 70 levers and treadles; Figs. 11, 12 and 13 are detail views of the twisting mechanism, on an enlarged scale, Fig. 11 being a sectional plan on line 11—11 of Fig. 2, Fig. 12 a sectional elevation on line 12—12 of Fig. 3, and Fig. 13 is a fragmentary detail looking at 75 the face of the twisting head.

The framework of the machine should have considerable strength and rigidity, and may conveniently be made up of suitably shaped and assembled lengths of angle iron. Thus, as illustrated in the drawings, there are three pairs of standards, *a*, *b* and *c*, the two standards of each pair being tied together, transversely of the machine, by angle iron cross braces *d*, and the sets of standards being tied together longitudinally of the machine by the upper T irons *e* which overlie the tops of the standards and form the upper surface of the framework, and by 80 intermediate T irons *f* which act as braces.

The bundle table is formed of two heavy castings *g* and *g'*, extending transversely of the machine and bolted to the upper flanges 100 of the T irons *e*. Between these castings, at the upper edges thereof, extend a series of rollers *h*. Six are shown in the drawing, though more or less may be employed. These rollers constitute the bundling table 105 and, by reason of the fact that they are rotatably mounted, it becomes easy to roll a bundle into position beneath the twister.

For the purpose of securely clamping the bundle in position on the table during the twisting operation, the head-plate *i* which carries the twister and which is so mounted that it may be reciprocated vertically, also carries forwardly projecting presser arms to press down upon the bundle when it is in position on the table. The manner of mounting and mode of operation of the head-plate will be understood from Figs. 1, 2, 3 and 5. The plate *i* is adjustably mounted in a frame *i'*, which is capable of moving vertically in guide ways in a casting *j*, which may be made integral with, or supported on, the cross bar *d* which joins the standards *b*, *b*. The frame *i'* has a depending tongue *i*², by which it is reciprocated vertically through the foot levers and mechanism illustrated in Figs. 1, 2, 9 and 10. From these figures it will be seen that there is a shaft *k* journaled in bearings in cross bars *k'* extending between the standards *a*, *a* and *b*, *b*. Rigidly fastened to this shaft, at the forward end, are two foot levers or treadles *l* and *l'*, and rigidly fastened to the shaft at its rear end is a lever arm *m* having a slot which receives a pivot pin *m'* of the toggle mechanism comprising the two arms *n* and *n'*, of which the arm *n* is fastened at its upper end to the stationary casting *j* and the arm *n'* is fastened at its lower end to the lower extremity of tongue *i*². From an examination of these figures it will be seen that when the short treadle *l* is pressed down the toggle is thrown to the right, as viewed in Figs. 3 and 9, or to the left as viewed in Fig. 2, and the frame *i'*, carrying with it the head-plate *i* and the twister, is elevated by the springs *o* which are fastened at their lower ends to the frame *i'* and at their upper ends to a cross bar of the machine. When the long treadle *l'* is pressed down the toggle is thrown to the other side of the center, as illustrated in Fig. 10, thereby depressing the frame *i'*, head plate *i*, and twister, and by contact of the end of treadle *l'* with the floor the toggle is stopped just beyond the center and the head-plate is retained in depressed position. Extending forwardly from the upper end of the slide *i* are the presser arms *l*³, which come down upon the bundle to clamp it in place, as illustrated in Fig. 1. The range of movement of these parts is such as to permit the ready placing of a bundle of predetermined size beneath the presser arms *l*³, when the head-plate is in its elevated position, but to clamp the bundle firmly on the table when the head-plate is depressed. By virtue of the toggle arrangement the parts stay in the position to which they have been brought, without necessitating that the operator should keep his foot on the treadle, or otherwise lock it in depressed position.

If the size of the bundle to be tied is ma-

terially changed it is necessary to adjust the position of the slide *i* in the frame *i'*. For this purpose there are provided journal bearings *p*, with lock pins *p'*, extending from the frame *i'*, and in these bearings is journaled a shaft *q* having outside of the framework of the machine a hand-wheel *q'*, and carrying a pinion *r* which meshes with a rack *r'* on the slide *i*. When the slide *i* is to be adjusted in the frame *i'* the locking pins *p'* are loosened and the hand-wheel *q'* turned so that by the turning of the pinion *r* in engagement with the rack *r'* proper adjustment is made. The locking pins *p'* are then re-set to lock the parts in the adjusted position.

The adjustable head-plate carrying the twister and presser arms, as above described, is not claimed to be broadly new at the present date, but on the contrary, is an improvement upon the mechanism for the same purpose illustrated and described in the United States Letters Patent above referred to. The most important advantage of the present construction, as compared with the construction of that patent, so far as the operation of reciprocating the head-plate is concerned, and the feature of novelty in respect thereto which is now particularly claimed, resides in the toggle arrangement of the arms *n* *n'* and the treadles *l* *l'* arranged to operate the same, whereby the head-plate may be easily elevated or depressed by an operator at the front of the machine, in a position to handily place bundles on the bundling table, and whereby the parts remain in the position to which they are thrown, that is, either in the elevated or in the depressed position, as the case may be, so that the operator's attention may not be taken up during the bundling operation, with the actuation of the clamping mechanism.

For the purpose of twisting together the two ends of the wire loop after it has been placed about the bundle, and for cutting the two ends to complete the tie, there is employed in the present machine, a twister substantially like that of the United States patent above referred to. This twister is fully illustrated in Figs. 3, 11, 12 and 13, of the drawing. From these figures it will be seen that at the center of the upper extremity of the head-plate *i* the head-plate is cut away to form rounded lips *s* which are continued into register with a straight slot *s'* in a wire gripping plate *s*² attached to the face of the rotatable twister head *s*³. This twister head is journaled at its forward end in the body of the head-plate *i*, and at its rear end has an extended hub journaled in a supporting plate *t* bolted to the head-plate *i*, as shown in Fig. 12. The twister head has a central bore *u* of considerably greater diameter than the wire, and a radial slot *u'*

which registers with, but preferably is larger than the straight slot s' in the gripping plate s^2 . The result of this construction is that the twisting wire is gripped by the gripper plate alone, and is free from the remainder of the twister head, so that it may be easily removed after the twisting operation is concluded and the wire has been cut off. The cylindrical twister head s^3 has on its periphery gear-teeth v , which mesh with corresponding teeth on a large hand-wheel v' , so that for each revolution of the hand-wheel a number of revolutions are imparted to the twister head, and since the two ends of the wires lie in the slot s' , the ends will be twisted together as shown in Fig. 11. The mechanism for cutting off the wire, as employed in the present case, is also substantially identical with that of the aforesaid patent. It is best illustrated in Figs. 2 and 11, and comprises an actuating cam w secured to the forward end of the shaft of hand-wheel v' , and actuating a swinging stop w' , which lies against the end of the cutting-knife w^2 , which knife is normally withdrawn into the position illustrated in Figs. 2 and 11 by the spring w^8 . When the hand-wheel is turned the cam w , acting through the swinging stop w' forces the knife w^2 forward past the end of slot s' and cuts off the wire. The hand-wheel v' is then turned in the reverse direction until the straight side of cam w lies against the lower end of stop w' in which position the slot s' will register with the opening between the lips s . It will be seen that, as best shown in Figs. 1 and 12, the bottom of the slot s' is well below the undersurface of the presser arms 7^2 , so that the twist is brought well below the edge of the bundle, and a clamping dog x (best seen in Fig. 2) is pivoted at x^2 at one side of the slot in the twister, and is provided with a handle x^2 , whereby it may be turned on its pivot to force the upper strand of the binding wire down below the edge of the bundle into the twisting position.

The reel for the binding wire is adjustably mounted on an upright rod or post in a bracket at the rear end of the machine, as shown in Fig. 1. It comprises a base plate A having four slots, in which are adjustably arranged four upright tapering posts A' having laterally extending feet as shown, and provided with locking nuts to hold them in adjusted position, as best shown in Fig. 8. To provide a level support for the wire, in which it will not catch, it is advisable to drop down over the posts A' , so as to rest on the feet, an annular thin metal plate A^2 , as shown, and in order that this plate may be conveniently packed for transportation, it is made in two hinged sections as shown in Fig. 4. On this plate the wire will rest smoothly, and in conjunction with

the apparatus about to be described the plate assists in preventing overrunning and tangling of the wire.

Extending from the head-plate i , and moving up and down therewith, is a bracket arm B , carrying a horizontal bar B' having upstanding end pieces B^2 , provided with guiding eyes for the binding wire (see Fig. 11). Sliding on the bar B' is a gripping device made up of a sliding block C with which co-acts to bind the wire a pivoted gripping cam C' connected by the link C^2 to the lever D , which has a forwardly extending handle as shown in Fig. 1 so that it may be within the reach of an operator at the front end of the machine. This lever is pivoted at D' to a depending arm D^2 attached to the outer end of the bar B' , and this bar and the depending arm are braced and stayed by a diagonally extending brace E , as shown in Fig. 1. For the additional purpose of stiffening these parts, and bracing the reciprocating head-plate i , a transverse bar F is bolted to the top surfaces of the longitudinal frame members e , and this bar carries a heavy upright F' , which engages with and braces the bracket arm B . Since the bracket arm B has an up and down movement with respect to the upright F' it is convenient to form a guiding groove in the bracket arm, which receives the upright, as illustrated in Figs. 4 and 11. It will be understood at once that this construction is such that when the lever D is drawn forward the gripping cam C' is turned into such a position that it does not grip the wire, and the block C slides freely forward on the bar B' . On the backward movement of the lever D the gripping cam is turned into such a position as to grip the wire, and it pulls the wire backward toward the wire reel, thereby tightening it about the bundle. The forward and backward movement of the lever arm D may be repeated as many times as is necessary to effectively tighten the wire about the bundle. This arrangement not only pulls the wire backward but it does so through a long leverage, so that the operator is enabled to draw the wires very tight. Furthermore, when the wire has been drawn as tight as possible the clamp C' still retains its gripping position, so that when the handle x^2 is thrown down to cause the clamping dog x to force the upper strand of the wire down below the upper edge of the bundle, the loop of binding wire about the bundle is still further tightened, as will be understood.

An important feature of a machine for the purpose intended is the provision of means to prevent overrunning of the wire reel and the unwinding of an undue amount of wire, which would become tangled and interfere with the next binding operation. This is particularly important in view of

the fact that in the normal operation of the machine it is necessary, for each bond or tie, to draw off in the first instance a greater quantity of wire than is actually employed in making the bond or tie after the wire has been tightened about the bundle. In the present machine this important feature is fully provided for in a manner which will now be described.

10 By referring to Figs. 1 and 8 of the drawing it will be seen that on the upright post which supports the wire reel, there is a retaining collar G on which rests the hub of a ratchet disk G', which is free to turn upon the post. The upper face of this ratchet disk G' is provided with a friction disk of rubber, leather, or the like, as seen in Fig. 8, and upon this rests a second friction disk on the lower end of a spring drum I. 15 Surrounding the upper end of the supporting post is another collar H and between this and the upper end of the hub of spring drum I is a coiled spring, which tends to force together the faces of the friction disks 20 between the drum I and the ratchet disk G'. The base plate A has a central depending hub G² which surrounds the hub of spring drum I and turns freely thereon, the base plate being held in place by the collar 25 H². Connection between the hub G² and the spring drum I is made through a coiled band spring I'. Extending from the periphery of the drum I is a projection I¹ and two pins I² (see Fig. 1) depending 30 from base-plate A to act with this projection to apply the tension of spring I' to the wire-reel in such manner as to keep the wire under tension as will be understood from the description of the mode of operation of the parts as given below. Turning 35 loosely on the hub of the ratchet disk G' (see Fig. 7) and supported on collar J', is a lever arm J which is connected by link L to lever D. The arm J carries a 40 pawl K pressed by spring K' into engagement with the teeth of the ratchet disk G'. The object of this connection is to turn the wire reel to wind up the wire as it is drawn back by the manipulation of handle D.

It is of great importance that the loop of wire which is to bind the bundle should be held exactly at right angles to the axis of the bundle during the bundling operation 45 and for this purpose the rollers h of the roller table are arranged in the supporting castings g and g' in such a manner that the middle rollers have an open slot or space between them, and at one or both ends of this slot, exactly in line with the axis of the twister (see Fig. 4) is a spring clip M, which grips the loop and holds it in the proper position. These clips have also the additional advantage that they hold the 50 loop open out of the way of the advancing

bundle and enable the operator, by pulling the wire with a jerk out of the clips, to draw it more tightly about the bundle than would otherwise be possible. These clips add very greatly to the successful operation 70 of the machine in practice. In the drawings one has been shown at each end of the slot in the table, but the one at the end of the slot next the head-plate is the more important and the other may be omitted without materially reducing the advantages attained. The small grooved roller s¹ best seen in Fig. 11, serves as a further guide for the binding wire and as a convenient anvil for the clamping dog x.

The operation of the machine in tying bundles is as follows: The hand wheel v having been brought to such position that the radial slot s' in the twister registers with the lips s₁ as illustrated in Fig. 13, a 85 loop of the binding wire is formed by grasping the end of the wire just in front of the forward guide B², and drawing from the reel enough wire to form a large open loop. The end of the wire is then laid in the slot s', 90 with its extremity bent laterally at the end of the cylindrical chamber u, as illustrated in Fig. 11. The loop is then pressed down over the guide roller s¹ and between the jaws of the spring clamp M which is next to the 95 head-plate. In this way that side of the loop is kept out of the path of the oncoming bundle. The other side of the loop may also be forced into the spring clamp M at the front of the bundling table, if such a clamp 100 is provided, thereby further insuring the proper position of the loop and its freedom from interference with the bundle. The bundle is then run on to the table through the loop, is pressed back against the face of 105 the head-plate as shown in Fig. 1, and the treadle U is thrown down to depress the head-plate and bring the presser arms L into clamping engagement with the top of the bundle. The operator then grasps the front 110 side of the wire loop and pulls it, with a short jerk, tightly about the back of the bundle, and at the same time manipulates the lever D several times to pull the wire back and draw it tightly over the top of the 115 bundle. This operation is usually completed by a series of short, quick movements of the lever D resulting in jerks on the binding wire, to draw out all the kinks and bends. While the wire is still gripped by cam C', 120 and with the operator still pushing back on the lever D, the clamping dog x is thrown down to press the upper strand of the wire down to the twisting position. This further tightens the wire as will be readily understood. The hand wheel v is then sharply rotated to twist the two ends of the loop and cut the wire off. At each backward movement of the lever D the link L imparts a 125 backward throw to the arm J and through 130

the pawl K, turns the ratchet disk G'. The friction between the friction disks, due to the spring between the collars H and H², and to the weight of the wire and wire reel is so great that this movement of the ratchet disk G' carries with it the spring-drum I and the wire reel to wind up the wire. It will be observed that the tendency of the spring I' is to turn the wire reel in such a direction as to wind up the wire, but this turning is stopped by the engagement of the forward pin I² with the projection i⁴, since when the parts have come into that position the spring is so far unwound that it will not carry the drum I around, because of the friction between the friction disks. When the wire is pulled off of the reel the first part of the movement turns the reel, winding up the spring I', and this winding of the spring continues until the rear pin I² engages the projection i⁴ and after that the reel and the spring drum I turn together, the friction of the friction disks being overcome and the ratchet disks G' being held in fixed position by the pawl K. The result of this construction is that there is always a tendency, due to the spring I', for the reel to wind the wire up, and the unwinding is always against this spring tension at first, and afterward against the friction of the friction disks. In this way overrunning of the reel is prevented and there is always a slight backward pull on the wire. The degree of this backward pull, due to spring I' may be varied by taking the rear pin I² out of the hole in which it is shown in the drawings and inserting it in another one of the series of holes disposed about a circle in the base-plate A. Four such holes are shown in Fig. 4.

What we claim is:

1. A bundling machine having means for forming a tie of binding wire about the bundle, said means including gripper mechanism adapted to grip the wire, and an actuating lever connected to the gripper mechanism and adapted to reciprocate it to draw the wire tightly about the bundle; substantially as described.

2. A bundling machine having means for forming a tie of binding wire about the bundle, said means including gripper mechanism adapted to grip the wire, and an actuating lever connected to the gripper mechanism and adapted to reciprocate it to draw the wire tightly about the bundle, a wire reel, and connections between the actuating lever and the wire reel adapted to rotate the reel to wind up the wire as it is drawn back by the manipulation of the lever; substantially as described.

3. A bundling machine having means for forming a tie of binding wire about the bundle, said means including gripper mechanism comprising a horizontal bar, a block

sliding on the bar, a gripping cam co-acting with the block to grip the wire, and an actuating lever operatively connected with the gripping cam and adapted to throw the cam into gripping position and to slide the block along the horizontal bar in a direction to draw the wire tightly about the bundle; substantially as described.

4. A bundling machine having means for forming a tie of binding wire about the bundle, said means including gripper mechanism comprising a horizontal bar having upstanding guide members for the wire, a block sliding on the bar, a gripper cam co-acting with the block to grip the wire, and a lever operatively connected to the gripper cam and adapted to throw it into the gripping position and to slide the block along the bar to draw the wire tightly about the bundle; substantially as described.

5. A bundling machine having a bundling table; a head-plate mounted for vertical reciprocation at one side of the table, presser arms carried by the head-plate and adapted to clamp the bundle on the table, and means for forming a tie of binding wire about the bundle, said means including gripper mechanism comprising a horizontal bar supported from the head-plate and moving vertically therewith, a block sliding on the bar, a gripper cam co-operating with the block to grip the wire, and an actuating lever operatively connected to the gripper cam and adapted to throw it into gripping position, and to slide the block on the bar in a direction to draw the wire tightly about the bundle; substantially as described.

6. In a bundling machine, a wire reel, a rotatable hub on which the reel is rotatably mounted, a spring connection between the reel and hub, a positive connection between the reel and hub which is established after an initial turning movement during which the spring is put under tension, a support for the hub, and a friction device interposed between the hub and its support whereby the initial unwinding of the wire tensions the spring, and then through the positive connection rotates the reel and hub against the frictional drag; substantially as described.

7. In a bundling machine, a wire reel, a hub on which the reel is rotatably mounted, a spring connection between the reel and hub, and a positive connection between the reel and hub which is established after an initial turning movement during which the spring is put under tension, whereby tension is applied to the wire as it is withdrawn from the reel; substantially as described.

8. In a bundling machine, a wire reel, an upright supporting post therefor, a supporting plate on the post, a spring drum resting on the plate, friction mechanism interposed between the spring drum and the support.

ing plate, the reel resting on the spring drum, and a spring connected at one end to the reel and at the other end to the drum; substantially as described.

9. A bundling machine having a bundling table, a head-plate mounted for vertical reciprocation at one side of the table, presser-arms carried by the head-plate and adapted to clamp the bundle on the table, means for forming a tie of binding wire about the bundle, said means including gripper mechanism supported from the head-plate and moving vertically therewith, and adapted to grip the wire, and an actuating lever connected to the gripper mechanism and adapted to reciprocate it to draw the wire tightly about the bundle; substantially as described.
10. A bundling machine having a bundling table, a head-plate mounted for vertical reciprocation at one side of the table,

presser-arms carried by the head-plate and adapted to clamp the bundle on the table, means for forming a tie of binding wire about the bundle, said means including gripper mechanism supported from the head-plate and moving vertically therewith, and adapted to grip the wire, an actuating lever connected to the gripper mechanism and adapted to reciprocate it to draw the wire tightly about the bundle, and an upright guiding brace for the gripper mechanism; substantially as described. 25
